UNITED STATES PATENT OFFICE.

WILLIAM PHILLIPS, OF CHICAGO, ILLINOIS.

AUTOMOBILE-RADIATOR.

1,391,500.

Specification of Letters Patent. Patented Sept. 20, 1921.

Application filed October 2, 1918. Serial No. 256,506.

To all whom it may concern:

Be it known that I, WILLIAM PHILLIPS, a citizen of the United States, residing at Chicago, county of Cook and State of Illinois, have invented certain new and useful Improvements in Automobile-Radiators, of which the following is a specification.

This invention has relation to improvements in automobile radiators used in connection with the water cooling systems for gasoline engines and the principal object is to provide more perfect circulation of the water cooling element through the radiator.

Another object of the invention is to, in a greater degree, provide for the passage of the water and its associated air cooling element over a comparatively large area.

Another object of the invention is to subject the water cooling element to a tortuous 20 passage through the radiator.

It is also a further object of the invention to provide a device of the character set forth, which is simple of construction and assembly, economical to manufacture and 25 which can be used in connection with any type of gasoline power plants.

With these and many other objects in view, an embodiment of the invention has been illustrated in the accompanying drawing, and novel features have been pointed 30 out in the appended claims.

In the drawings:

Figure 1, is a fragmental perspective view of a radiator casing and cluster of radiator 35 units.

Fig. 2, is an enlarged front elevational view of the units.

Fig. 3 is an enlarged horizontal cross sectional view on line 3--3 of Fig. 2.

Fig. 4, is an enlarged vertical sectional view on line 4--4 of Fig. 3, and

Fig. 5, is an enlarged perspective view with portions in section, showing the nesting arrangement of the units.

The usual or common type of radiators for water cooling systems for gasoline engines, comprise a series of units which are nested in such manner as to provide longitudinal passages for the circulation of the water cooling element and transverse tubes for the introduction of the air cooling medium and in the embodiment of the present invention, the above related units are individually designated by the numeral 1.

The units 1, in their initial state, comprise strips of sheet metal, preferably brass,

which are subjected to the action of a stamping machine or press and consequently, when folded over at their medial part, assume the character of longitudinal plates 2 and 3, 60 which together with others of similar construction are assembled or nested together to form a complete radiator. Thereby, when the said strips are folded over, to dispose the plates 2 and 3 in alinement, the concavities and projections resultant of the stamping operation are positioned in opposed relation or registration and tortuous or restricted water passages are formed.

In the stamping operation of each of the 70 elongated unit sheets 1, the metal is struck outwardly to form a plurality of semi-hexagonal offset members 4 and 5, which are disposed in staggered relation the entire length of the strip.

The stamping of the series of offset members 4 and 5, forms flat narrow portions therebetween, and each alternate portion comprises the narrow vertical sides 6, of the semi-hexagonal offset members 4 and 5. 80 The other two relatively long sides 7 and 8 of the offset members 4 and 5, are disposed at an angle of approximately 35° from the point of intersection with the narrow vertical sides 6 and when the plates are folded, 85 the semi-hexagonal members 4 and 5, unite, in forming perfect hexagonally shaped tubes, which, as has been stated, are adapted for the passage of the air cooling medium through the radiator.

The construction of each individual sheet will be described and simultaneously with the above stamping operation the sheets 1 are struck outwardly at their longitudinal edges to form the flanges 10, which latter 95 project from the surface of the metal on the sides 6, 7 and 8. These flanges 10, attain their greatest height on the alternate vertical sides 6, and gradually decrease and terminate at the intersection of the long angular sides 7 and 8, with the alternate vertical sides 6.

At a point approximately central of the sheets, the metal is struck outwardly to form the offset flanges 11, which arise from 105 the point of intersection between the oppositely disposed vertical sides 6 and the long angular sides 7 and 8, and gradually increase in height toward certain of the short vertical sides 6. The faces 12 of the angular 110 portions of the offset flanges terminate in vertical connecting portions 13, each alter-

nate vertical side 6, carrying the said connecting portions 13, which latter are provided with laterally directed semi-circular passages or ports 14, in this connection it 5 may be stated, that the height of the offset flanges 11 is greatest at their point of connection with the vertical sides 6, this height gradually diminishing toward the point of intersection with the opposing vertical 10 sides 6.

Each alternate vertical side 6, is formed with a semi-circular depression 14' and when the sheets 1 are folded over to dispose the plates 2 and 3, in alinement, the flat 15 angular faces of the opposing flanges 10 and the opposing offset flanges 11, overlap, and the opposing semi-circular passages 14 and depressions 14' unite to form circular openings 15.

20 Each individual radiator unit or sheet 1, comprising the longitudinal plates 2 and 3 in their nesting arrangement, are assembled in such manner that every alternate unit has its plate ends folded over as illustrated at 25 16, and the opposing units are so positioned, that the medial creased portions 17, are disposed between the vertical sides 6, of the units which are folded over.

30 This arrangement as will be readily seen, provides restricted water spaces 9 between the plates 2 and 3 of the assembled sheets and through the circular openings 15.

By the provisions of the offset flanges 11, the water radiating space in each unit is 35 divided into two compartments or columns, which are in communication with each other through the circular passages or ports 15 and the water element in the tank will gravitate through the restricted passages 9, 40 between the plates 2 and 3 and a large portion of the water will pass from one compartment to the other.

It is understood, that the water compartment or columns in the front of the radiator 45 proper, receives the greatest influence of the air cooling medium, and as this cooled water is drawn out by the pump, not illustrated, an immediate displacement of the water in the opposing column is effected, which results in the passage of this water into the 50 front column through the restricted passages 15.

As the above operation or circulation continues, the heated water naturally has expansive tendencies and this results in the further circulation of the same and naturally a large amount of it will pass into the front columns.

A certain amount of water will gravitate 60 downwardly through the restricted passages 9 between the offset members 4 and 5, such passages being formed by the flanges 10, which as has been heretofore stated, project outwardly from the surface of the offset 65 members.

The hexagonal conformation of the tubes comprises a relatively large area for the contact of the air with the walls of the said tubes, formed by the long angular sides 7 and 8 and the vertical side 6, and the water during 70 its tortuous passage through the restricted passages is subjected to a maximum degree of cooling influence.

It will thus be seen that not only is a great air cooling influence provided, but the water 75 element is circulated through the radiator units in a relatively fine sheet and a part of the water is constantly circulating from one column to the other through the circular openings or passages 15.

80 The interlocking or overlapping function of the offset flanges 11, forms a wall or barrier between the two columns and the only communication is through the aforesaid passages 15.

85 The radiator units are arranged in the manner illustrated in Fig. 1 and the folded over end portions 16 are soldered and such sealing action forms each sheet 1, into a separate unit having a plurality of air tubes, 90 and such nesting provides restricted passages 9 between the units.

When the units are assembled the upper and lower ends are dipped in solder so that the radiator is hermetically and water 95 sealed.

95 It is obvious that with this arrangement a thorough circulation of the water element is effected and the same is diverted and passed from one chamber or column to the 100 other, and during such tortuous passage is subjected to a high degree of cooling influence and likewise a high degree of air contact space is afforded, by the hexagonal configuration of the tubes.

105 It is manifest that modifications and changes may be made which will not depart from the spirit of the invention, and therefore I do not limit myself to the constructional features shown, but claim the invention as broadly as the art permits.

I claim:

1. An automobile radiator comprising a plurality of units adapted for nesting arrangement to form hexagonal air inlet tubes 115 and vertical water cooling passages, and including in said units angular projections of similar configuration in each unit, said projections also being adapted for nesting in each other and adapted to form obstructions 120 in the vertical water cooling passages thereby separating said water cooling passages into a plurality of vertical compartments, the projections being equipped with recesses supplementing each other to form circular passageways leading from one of said compartments to another.

125 2. An automobile radiator comprising a plurality of units adapted for nesting arrangement to form hexagonal air inlet tubes 130

- and vertical water cooling passages, said units being provided intermediate their ends with projections of angular outline and adapted to divide, when the units have been placed in operative position, the substantially vertical water passages into a plurality of substantially vertically arranged compartments, each of said projections being provided in its medial portion with a semi-cylindrical horizontal recess whereby communication between the substantially vertical compartments formed by said obstructions is produced.
- 5 In testimony whereof I affix my signature in the presence of a witness.

WILLIAM PHILLIPS.

Witness:

DANIEL A. BRENNAN.
